JAR

Jon Stengren, Forest Hills, N. Y.

Application August 14, 1950, Serial No. 11,755

Term of patent 3½ years

(Cl. D58—25)

To all whom it may concern:

Be it known that I, Jon Stengren, a citizen of the United States residing at Forest Hills, in the county of Queens and State of New York, have invented a new, original, and ornamental Design for a Jar, of which the following is a specification, reference being had to the accompanying drawing, forming part thereof.

In the drawing

Fig. 1 is an exploded side elevational view of a jar showing my new design;

Fig. 2 is a front elevational view thereof; and Fig. 3 is a top plan view thereof.

I claim:

The ornamental design for a jar, substantially as shown.

JON STENGREN.
